UNITED STATES PATENT OFFICE.

CURTIS SYLVESTER PEARCE, OF BIG ISLAND, VIRGINIA.

CISTERN-CLEANER.

1,219,763.

Specification of Letters Patent. Patented Mar. 20, 1917.

Application filed November 16, 1916. Serial No. 131,736.

To all whom it may concern:

Be it known that I, CURTIS S. PEARCE, a citizen of the United States, residing at Big Island, in the county of Bedford and State 5 of Virginia, have invented certain new and useful Improvements in Cistern-Cleaners; and I do declare the following to be a full, clear, and exact description of the invention, such as will enable others skilled in the art 10 to which it appertains to make and use the same.

This invention relates to improvements in tank or cistern cleaners, the object being to provide a simply constructed device whereby 15 dirt or other sediment on the bottom of the tank or cistern may be readily removed without stirring up the water therein.

An additional object is to provide a very simply constructed device of this character 20 having means for regulating the size of the openings of the cleaning attachment.

Still another object is to provide a very simply constructed cistern cleaner which may be formed of sheet metal in a very in 25 expensive manner.

With these and other objects in view, the invention resides in the novel features of construction, combination and arrangement 30 of parts which will be hereinafter particularly described and claimed and shown in the drawings wherein:

Figure 1 represents a vertical sectional view of a portion of a cistern showing my improved cleaner disposed therein, the latter 35 being in side elevation;

Fig. 2 is also a side elevation of the device viewed at right angles to Fig. 1;

Fig. 3 is a horizontal section on the plane of the line 3-3 of Fig. 4; and

Fig. 4 is a vertical section on the line 40 4-4 of Fig. 2.

In the accompanying drawings I have illustrated the preferred form of my invention, it being shown disposed in a tank or 45 cistern 1 of ordinary formation. That part of the invention which is disposed at the bottom of the cistern consists of a flat rectangular box-like member 2 having a flat top and bottom 3 and 4 respectively. The

50 top has a vertically extending attaching rib 5 formed thereon to which the lower end of a suitable handle 6 is pivoted as shown at 7, the lower end of the handle being preferably bifurcated to straddle said rib. By 55 this means the member 2 may be readily moved about within the cistern.

The object of this member 2 is to loosen the sediment at the bottom of the cistern so that it may be drawn into the same and sucked up through a pipe 8 to the top of 60 the cistern, or above the surface of the ground where the latter is sunk below the level of the earth. Any preferred means may be provided for creating suction in the pipe 8, such as a hand or machine operated 65 pump (not shown). The pipe 8 is preferably flexible and carries at its lower end a suitable coupling by which it may be attached to the upper end of a pipe section 9 which projects through the top 3 of the 70 member 2. The pipe section 9 extends within the member to a point adjacent the bottom 4 and is secured in said top by soldering or other preferred means.

In order that the dirt or other sediment 75 may be forced into the member 2, a pair of slits are provided therein, these slits being formed in the opposite sides 10 of the member. The most simple manner of forming these slits and that preferably used, consists in spacing the lower edges of the sides 10 from the bottom 4, thus producing horizontal openings 11 of uniform width throughout their length. Scrapers by which the sediment is loosened are formed by extending the bottom 4 beyond the sides 10 as shown at 12, these portions 12 being slightly downwardly inclined as shown. From the foregoing description it will be seen that the member 2 may be moved in either of two 80 directions to loosen the dirt in the bottom of the cistern 1, and cause it to be sucked into the body of the member from whence it is readily removed by the above mentioned pump. 95

In case the pump is not sufficiently strong or is not operating properly, it becomes necessary to reduce the size of the slits or openings 11 so as to create more suction. In order to accomplish this, a spring metal 100 plate 13 is spaced a slight distance away from each of the sides 10, the ends of each of these plates being bent laterally as at 13' and secured to the other sides 10' of the member 2. These spring metal plates 13 are 105 slightly less in width than the sides 10 and are adapted to force a plurality of flat plates 14 against the sides 10 to hold them in position, the lower ends of these plates 14 covering either one or both of the slits 11. Any 110 number of flat plates 14 may be provided and the slit may be either wholly or par-

tially covered thereby. It will be seen that these plates project above the top 3 of the member so that they may be readily removed from between the spring metal plates 13 and the sides 10.

This means provides a very simple arrangement whereby the member 2 may be adjusted to accommodate various degrees of suction. Since all of the parts of the device are very simple in their nature and may be formed of light gage sheet metal, the invention may be very inexpensively manufactured and marketed.

I claim:

15 1. A device of the class described comprising a flat box, the opposite edges of the bottom thereof being extended beyond the sides to form scrapers, the sides of said box adjacent said scrapers having narrow horizontal slits formed by spacing the lower edges of said sides from the bottom, a handle connected with the top of said box, and means for removing material from said box.

25 2. A device of the class described comprising a box having inlet slits formed in its opposite sides adjacent its bottom, means for partially or wholly closing either of said slits, a handle connected with the top of said box, and means for removing material from said box.

30 3. A device of the class described comprising a flat box, the opposite edges of the bot-

tom of the box being extended beyond the sides to form scrapers, the sides of said box adjacent said scrapers having narrow horizontal slits formed by spacing the lower edges of said sides from the bottom, a spring metal plate disposed in close proximity to each of the sides containing said slits, said plates being secured by their opposite ends 40 to the other sides of said box, a plurality of plates adapted to be held by said spring metal plates to close said slits, a handle connected with the top of said box, and means for removing material from said box.

4. A device of the class described comprising a box, the opposite sides of said box having narrow slits adjacent the bottom, a spring metal plate disposed in close proximity to each of the sides containing said 50 slits, said plates being secured by their opposite ends to the other sides of the box, a plurality of plates adapted to be held by said spring metal plates to wholly or partially close said slits, a handle connected to 55 the top of said box, and means for removing material from said box.

In testimony whereof I have hereunto set my hand in the presence of two subscribing witnesses.

CURTIS SYLVESTER PEARCE.
